UNITED STATES PATENT OFFICE.

JULIUS LEVY, OF ROLAND PARK, MARYLAND.

TOEPODO-GUARD.

1,240,152.

Specification of Letters Patent. Patented Sept. 11, 1917.

Application filed December 5, 1916. Serial No. 135,141.

To all whom it may concern:

Be it known that I, JULIUS LEVY, a citizen of the United States, residing at Roland Park, in the county of Baltimore and State of Maryland, have invented certain new and useful Improvements in Torpedo-Guards, of which the following is a specification.

My invention relates to certain new and useful improvements in devices for protecting vessels at sea from being struck by marine torpedoes and the like, and it has for its object the provision of simple and effective means for stopping a torpedo at a sufficient distance from the vessel to prevent injury thereto.

More specifically the invention contemplates the provision of a series of screens or shields normally carried by the sides of the vessel just above the water line, so as not to retard the vessel, and having means whereby they can be quickly lowered into a position to protect the vessel from torpedoes or mines. The invention also includes improved locking means for holding the shields rigidly in position and for preventing them from yielding under the influence of the impact of a torpedo.

In order that the invention may be readily understood reference is had to the accompanying drawings forming part of this specification, and in which—

Figures 1 and 2 are conventional side elevations of a ship or the like showing my improved torpedo guards applied thereto and illustrating such guards in raised and lowered positions respectively.

Fig. 3 is a transverse section on an enlarged scale showing the guard on one side of the ship in operative position and that on the other side of the ship as folded into normal or inoperative position.

Figs. 4 and 5 are enlarged fragmentary details showing my improved holding or locking mechanism.

Fig. 6 is a perspective view showing one of the folding frames for supporting the screens;

Fig. 7 is a side elevation showing the additional manual locking means which I may employ; and,

Fig. 8 is a fragmentary side elevation showing a modified construction.

Referring to the drawings in detail 1 designates the hull of a ship or other vessel. Along the sides of such hull I provide

a series of pairs of vertically extending tracks 2 having slots or guideways 3 therein, as clearly shown in Figs. 4 and 5. As illustrated in Figs. 1 and 2 four pairs of 60 such tracks are shown on each side of the ship, each pair serving to support a separate screen or guard.

Each of these guards embodies a folding frame comprising a pair of arms 6 pivoted 65 at their ends to brackets 4, as indicated at 5, such brackets being rigidly secured to the sides of the ship at a point preferably just above the water line.

Pivoted between the outer ends of the 70 arms 6 is a rectangular frame comprising the horizontal members 7 and 9 connected by the transverse members 8. The ends of the member 7 are freely journaled in the arms 6 and the member 9 has pivotally connected thereto the ends of a pair of brace members 10. The other ends of the brace members 10 are bifurcated as indicated at 10 and are pivotally connected to blocks 11 80 adapted to slide on the ways or tracks 2. The pivot pin 12 connecting each brace 10 with its block 11 travels in the slot 3 of the track or guide.

Formed in each block 11 is a slot 13 through which the pivot pin 12 also passes, 85 such slot being disposed at an angle to the slot 3, as clearly shown in Figs. 4 and 5.

It will be seen that the braces 10 are disposed inside of the arms 6 and that when the inner ends of such braces are raised, the 90 frame formed of the members 7, 8, and 9 will swing upwardly against the under side of the arms 6, and that thereupon such arms, together with the frame, will swing upwardly into vertical position, as shown at 95 the left of Fig. 3.

In order to hoist the frames into such folded or inoperative position, I preferably provide cables 14 attached to the blocks 11 and passing upwardly over pulleys 15, suitably mounted above the deck of the ship. The cables 14 are wound upon drums 16, a separate drum being preferably provided for each pair of cables, as clearly shown in Figs. 1 and 2. Each drum 16 is 100 suitably mounted in pedestals 17, resting upon the deck 18, or other suitable part of the ship, and may be provided with a crank 19, by means of which it can be turned. Instead of the cranks, the drums may be rotated to hoist the screens by power operated means. In this case, the drums will pref-

erably be all connected by a common shaft 16^a, as shown in Fig. 8, and on this shaft may be secured a sprocket wheel 29, connected by a sprocket chain 30 with an electric or other suitable motor 31, as illustrated at the right of Fig. 3. Unwinding of the drums 16 in either case is prevented by means of a ratchet wheel 20 rigidly secured to the drum and adapted to be engaged by a pawl 21. This pawl is held in engagement with the ratchet wheel by means of a spring 22, the tail 23 of which bears against the pawl, as shown in Fig. 3. For releasing the pawl, a lever 23^a is provided, having a lug 24 so related to the spring 22 that when the lever 23^a is moved upwardly about its pivot, the lug 24 will engage the curved portion of the spring 22 in such a way as to cause the tail 23 to bear against the heel of the pawl and swing it out of engagement with the ratchet. Other suitable pawl and ratchet mechanism may, of course, be substituted without departing from the main features of the invention.

A screen, preferably composed of chain mesh, is secured to each frame, as indicated at 13^a. This screen is of sufficient strength to resist the impact of a torpedo and will probably cause the explosion thereof at a safe distance from the side of the ship.

A similar screen 13^b is also secured to the brace rods 10, as shown in Fig. 3, thus affording double protection to the ship.

Normally, the screens or guards will be folded as shown at the left of Fig. 3, but when passing through a danger zone the screens may all be lowered into operative position, as shown in Fig. 2, or at the right of Fig. 3.

It will, of course, be understood that for the purposes of illustration, the spaces between the screens in Figs. 1 and 2 are shown relatively much larger than would be the case in actual practice.

Referring again to Figs. 4 and 5, it will be seen that when hoisting the blocks 11 by means of the cables 14, the pivot pin 12 rests in the bottom of the slot 13 and travels freely up the slot 3, as shown in Fig. 4. When, however, a thrust is applied to the outer ends of the braces 10, such for example as would be caused by the impact of a torpedo with the screen, the pin 12 is driven upward in the slot 13, as clearly shown in Fig. 5, and caused to jam or wedge therein, thus preventing the block 11 from rising and securely holding the screen against movement. From the foregoing, it is apparent that I have provided means operated by the impact of a torpedo for holding or locking the screen against movement.

Additional manually operated locking means may be provided, if desired, and such an arrangement is shown in Fig. 7. This

locking means consists of a vertical shaft 25, extending down along the side of the ship and journaled in suitable brackets 26. The shaft is provided at its upper end with an operating crank 27, accessible from the deck or other suitable part of the vessel, and carries at its lower end a locking segment 26, adapted to be rocked into position to overhang the top of the block 11. After a screen has been lowered, therefore, the shafts 25 may be rotated and the blocks 11 positively locked in position, as shown.

It will, of course, be understood that when it is desired to lower any particular screen it is only necessary to raise the lever 23, associated with the corresponding drum. This disengages the pawl and permits the screen to drop by gravity into operative position.

What I claim is:

1. In a device of the class described, the combination with a vessel, of a folding frame carried by the side thereof, a net or screen secured to said frame, pivoted braces for holding said screen in operative position, means for hoisting the upper ends of said braces and thus folding said frame when desired, and means whereby a thrust against said screen serves to hold said braces against such movement.

2. In a device of the class described, the combination with a vessel, of a pair of arms pivoted to the side thereof, a screen carried by the outer ends of said arms, pivoted braces extending from the lower edge of said screen to the side of said vessel to hold the screen against movement, and means for shifting said arms and braces about their pivots into folded position against the side of the vessel and thus raising the screen above the water line.

3. In a device of the class described, the combination with a vessel, of a pair of vertical guideways carried by the side thereof, blocks working on said guideways, brace members secured to said blocks, a frame to which said brace members are pivoted, arms supporting said frame, and pivoted to the side of the vessel, and means for raising and lowering said blocks to shift said frame.

4. In a device of the class described, the combination with a vessel, of arms pivoted thereto, a frame and screen carried by said arms, brace members secured to said frame, blocks to which said brace members are connected, guideways on which said blocks slide, each of said guideways having a slot, each of said blocks also having a slot crossing the first mentioned slot at an angle, and a pin secured to each brace rod and passing through both of said slots, whereby a thrust along said brace members will cause said pins to bind in said slots, and prevent movement of said blocks.

5. In a device of the class described, the combination with a vessel, and a guard car-

ried thereby, of a vertically sliding member for raising and lowering said guard, and manual means for locking said sliding member against movement after said guard has 5 been lowered into operative position.

6. In a device of the class described, the combination with a vessel, of a folding frame carried by the side thereof, a net or screen secured to said frame, braces extending from the lower edge of said frame to

the side of the vessel to hold said frame in operative position, and a second net or screen secured to said braces.

In testimony whereof I affix my signature, in presence of two witnesses.

JULIUS LEVY.
